This invention relates to lamps for vehicles, but particularly to dome lights used in the inside of vehicles; and an object is to produce a simple and efficient structure of this character having the novel features of construction and arrangement for adapting the device for commercial manufacture at a relatively low cost and at the same time providing an assembly, the parts of which can be quickly and conveniently put together without the use of special tools.

Another object is to produce a dome light assembly having the improved features of construction and design hereinafter described.

A cardinal feature of this invention comprises a housing which is formed with an open end, outwardly from which extends a flange. Mounted on this flange in telescopic engagement therewith is an inwardly-extending flange integral with a one-piece lens and rim member. The rim portion of the member extends laterally from the lens portion and provides the sole rim for both the housing and the lens, and the rim portion terminates in a plane coincident with the inner end of the housing flange. A lens is also provided a part

25 The invention is shown by way of illustration
on the accompanying drawing, in which:
Figure 1 is a top plan view of a dome light
structure viewed from the lens side,

Figure 2 is a transverse sectional elevation on the line 2--2 of Figure 1;

Figure 4 is a fragmentary plan view of a dome light assembly in which a switch is employed; and

Figure 5 is a transverse sectional view on the line 5—5 of Figure 4 showing the manner in which the switch lever projects through an opening in the rim.

40 the following:
This application constitutes a division of my co-pending application Serial No. 35,354 filed August 8, 1935 and entitled "Dome light assembly".

45 In the form of the invention shown in Figures 1 and 2, the dome light assembly consists of a base or housing 10, which is preferably a sheet metal stamping and is cup-shaped to receive a bracket consisting of a base 11, which lies flat 50 against the rear wall of the housing to which it is secured by a rivet 12, and a socket portion 13 integral with the base 11 and extending outwardly therefrom at an inclined angle. A bulb 14 is adapted to be mounted in the socket portion 13 to be positioned at an acute angle with

VEHICLE LAMP

respect to the rear wall of the housing. A spring contact plate 15 is adapted to engage the rear end of the lamp and is held to a side wall of the housing by a post 16, insulating washers 17 and 18 insulating this post from the adjacent parts. It will be understood that post 16 provides a live connection for the lamp 14, the ground connection 19 likewise engaging the side wall of the housing and being connected in the usual manner to the vehicle frame. 10

Extending laterally from the side walls of the housing 10 is a flange 20 which terminates in an outwardly extending flange 21 providing the open mouth for the housing. Covering the face or front portion of the housing is a lens 22 of translucent material, but preferably is of molded plastic material, such as Plaskon. The body portion of the lens bows outwardly, as indicated in Figure 2, so that the lamp bulb 14 is positioned closely to the under side thereof in such manner that the entire lens portion is illuminated and eliminating any shadows or dark spots. Integral with the lens and projecting inwardly therefrom is an annular flange 23, which is adapted to fit over the outside of the outwardly projecting flange 21 of the housing. The flange 23 is relatively thin and since the molded material, such as Plaskon, has a certain amount of resiliency, the lens is securely held in place due to the frictional engagement between the flanges 21 and 23, friction being relied upon solely to retain these parts in assembled relation. To provide a finished appearance for the assembly, a rim 24 provides a continuation of the lens portion 22 and inclines outwardly and inwardly from the flange portion 23, the end portion of the rim curving inwardly in this instance.

An important advantage of the dome light assembly above described resides in the fact that the entire lens portion is illuminated by the lamp 14 and the lens can be attached to the base or housing 10 without the use of screws, bayonet joints, clamping rings or other devices commonly used for these purposes. In this manner, applicant is enabled more readily to mount the lens and this can be effected at a lower cost. By mounting the lamp bulb 14 in the manner above described the housing or base 10 requires a less amount of metal, since it is considerably shallower than similar housings, so that the cost is likewise reduced in this manner. 45 50

In order to enhance the attractive appearance of the assembly, apertures 25 may be formed in the housing flange 21 and apertures 26 in the lens flange 23 in registry with each other to enable some of the light rays to pass therethrough.

and illuminate portions of the rim 24. The number and arrangement of these apertures may be varied as desired, depending on the desired effect.

In the form shown in Figure 3, the base or housing 10b is of molded insulating material, such as Plaskon, which eliminates the necessity of using insulating washers between the live post 16b and the ground connection 19b, the latter serving to secure the base 11b of the lamp bracket to the housing. It will also be noted that the rear wall of the housing 10b is inclined thereby to provide a more efficient reflecting surface for the light rays and also to effect a substantial saving in material. In this instance, the lens, which is also of molded plastic material, is similar to that shown and described in connection with Figure 2, although the openings 25b and 26b in the housing and lens flanges, respectively, may or may not be used as desired.

20 It will be apparent that the structures above described do not employ a switch formed as a part of the housing, such structures being connected with a pillar or other part of the vehicle. In the form shown on Figures 4 and 5 an elongate slot 29 is provided in the rim 24c through which extends a switch lever 30. In order to insure that the lens 22c is properly mounted on the housing or base, a groove 31 is formed in the flange 21c to receive a projection 32 formed in the lens flange 23c.

It is to be understood that numerous changes in details of construction, arrangement and choice of materials may be effected without departing from the spirit of the invention, especially as defined in the appended claims.

What I claim is:

1. A vehicle lamp comprising a housing having an open mouth, a peripheral flange at the mouth thereof, a one-piece lens and rim member of molded plastic material having the lens portion closing the mouth of the housing and the rim portion extending laterally of such opening, said rim portion merging into the lens portion with substantially continuous unbroken line, and a resilient flange integral with and extending inwardly from said member substantially at the junction of said rim and lens parts, said flanges telescoping with each other to hold the parts in assembled relation and said rim member termi-

nating at such point as to substantially conceal said flange members.

2. A vehicle lamp comprising a housing having an open end defined by a peripheral flange, a one-piece lens and rim member of molded plastic material having an inwardly extending resilient flange telescoping in frictional engagement with the housing flange, said resilient flange extending inwardly from said lens substantially at the junction of said lens and rim parts, the rim portion of the member extending laterally and providing the sole rim for both the housing and the lens. 5

3. A vehicle lamp comprising a housing having a mouth, a flange at the mouth and extending outwardly therefrom, a lens, a resilient flange integral with the underside of the lens and extending inwardly therefrom for telescopic frictional engagement with said housing flange, a laterally extending rim integral with said lens and terminating in a plane substantially coincident with the inner end of said housing flange. 10

4. A dome light assembly comprising a housing of molded plastic material and having an open end and a rear wall, a lamp bracket having a base fixed flat against said wall and a socket extending outwardly from said base, a ground connection leading from said base, a spring contact plate, a live connection on said rear wall for one end of said contact plate, a lens of molded plastic material having an inwardly extending flange 25 frictionally engaging said housing, and a rim integral with said lens and extending outwardly from said casing. 20

5. A vehicle lamp comprising a housing having a flanged outer end, a lens having an inwardly extending translucent resilient flange frictionally engaging said flanged end, and a translucent rim extending laterally of the junction between said second flange and lens, said flanged end being apertured to enable light rays from the housing 30 to illuminate a portion of said rim. 40

6. A dome light assembly comprising a housing having a flanged end, a lens having an integral inwardly extending resilient flange frictionally engaging said flanged end, and a rim extending laterally from said second flange, said rim and lens being of the same material and integral with each other. 45
